Application June 13, 1952, Serial No. 293,296

2 Claims. (Cl. 312—258)

This invention relates to cabinets, and more particularly sheet metal cabinets adapted to be folded for convenience in shipping and being arranged for easy assembly for use by the ultimate owner.

The main object of the invention is to provide a novel and improved cabinet adapted to be folded to a compact size for shipping, said cabinet being simple in construction, being easy to assemble, and being sturdy in construction.

A further object of the invention is to provide an improved metal cabinet adapted to be readily folded to a compact size for convenience in transportation and to reduce the cost of shipping thereof, said cabinet being inexpensive to manufacture, being easy to set up for use, and being neat in appearance.

Further objects and advantages of the invention will become apparent from the following description and claims, and from the accompanying drawings, wherein:

Figure 1 is a perspective view of an improved cabinet constructed in accordance with the present invention, shown set up for use.

Figure 2 is a perspective view of the main body portion of the cabinet of Figure 1, shown in folded position for transportation, one of the front doors of the cabinet being removed to facilitate illustration of the constructional details of the main cabinet member.

Figure 3 is a perspective view of the major components of the cabinet of Figure 1, shown in separated positions, preparatory to final assembly after the main body portion of the cabinet has been unfolded to its extended position.

Figure 4 is an enlarged fragmentary side elevational view showing portions of the marginal elements of the main body member of Figure 2.

Figure 5 is a horizontal cross sectional detail view taken through one of the doors of the cabinet of Figure 1, showing the reinforced construction thereof.

Figure 6 is a fragmentary top plan view of one of the side portions of the cabinet showing the manner in which the side panel is engaged on the cabinet side portion during the assembly of the cabinet.

Figure 7 is an enlarged horizontal cross sectional detail view taken on the line 7—7 of Figure 1 and showing the manner in which the side panel is engaged around the side portion of the main body member of the cabinet.

Figure 8 is a fragmentary front elevational view of an upper front corner portion of the front wall element of the cabinet.

Figure 9 is an enlarged vertical cross sectional detail view taken on the line 9—9 of Figure 3.

Figure 10 is an enlarged front elevational fragmentary detail view illustrating the construction of the lower left corner portion of the cabinet of Figure 1.

Referring to the drawings, the illustrated cabinet is designated generally at 11 and comprises a foldable main body 12 and the respective side panels 13, 13 which are detachably secured to the side portions of the main

2

body 12 when said main body is in the unfolded position thereof, as shown in Figure 3. The main body 12 comprises a rectangular back panel 14 formed with the vertical forwardly projecting side flanges 15, 15 and a plurality of rectangular shelves 16 and a top panel 17 of identical shape with the shelves, having their rear corners received between the side flanges 15 and being pivotally connected thereto, as by rivets 18. As shown in Figure 3, the shelves 16 and the top panel 17 are provided with the depending side flanges 19, and the rivets 18 extend through the end portions of said flanges 19. Designated generally at 20 is a front frame which comprises respective vertical channel-shaped corner posts 21, 21, said corner posts being provided with the side flanges 22 opposing the flanges 15 of the back wall panel 14. The front corners of the top panel 17 and the shelves 16 are received between the flanges 22 and are pivotally connected thereto, as by the rivets 23. As shown in Figure 3, the rivets 23 extend through the depending flanges 19 of the shelves 16 and the top panel 17, as well as through the flanges 22 of the posts 21.

The posts 21 are rigidly connected at their top ends by a horizontally extending flat bar 24 having the beveled ends 25 overlapping the top ends of the posts 21 and being welded thereto. The horizontal bar 24 is formed with the depending, rearwardly offset flange 26, and the post members 21 are likewise formed with the rearwardly offset flanges 27 which are in the same plane as the offset flange 26 of top bar 24. Rigidly secured to the lower portions of the flanges 27 are the respective ends of the flat, relatively wide horizontal bottom plate 28, which rigidly connects the lower portions of the post members 21, 21, thereby rigidifying the front frame 20. Designated at 29, 29 are the respective front doors hinged to the posts 21, 21 and defining closure means for the cabinet. As shown in Figure 5, each door 29 may comprise a sheet metal plate formed with the inturned marginal flanges 30, 30 and rigidified by the vertical longitudinal inner reinforcing channel 31 welded to its inside surface at the flanges 32, 32 of the reinforcing channel 31, as clearly shown in Figure 5.

Each of the side panels 13 comprises a generally rectangular body of sheet metal formed with a top flange 33, a flat vertical laterally inwardly projecting rear marginal flange 34 and a laterally inwardly projecting channel-shaped front marginal flange 35. The side panels 13 are adapted to fit closely over the side portions of the body 12 when said body is in its expanded position, as shown in Figure 3, with the channel-shaped flanges 35 of the side panels fitting closely over the posts 21 and the rear flanges 34 of the side panels engaged around the rear corners of the body in the manner shown in Figures 6 and 7. The side panels 13 are formed in the channel flanges 35 at 36 with bolt holes, a pair of bolt holes being located respectively near the top and bottom of each side panel, as shown in Figure 3. The bolt holes 36 in the short flange of the channel flanges 35 are adapted to register with similar bolt holes provided in the inside flange of the posts 21 so that bolts may be engaged therethrough for securing the flanges 35 to the posts 21 and so that said bolts will be subsequently concealed by the doors 29. Similarly, bolt holes are provided in the top and bottom corner portions of the rear panel 14 which are arranged to register with the bolt holes 36 in the top and bottom portions of the flanges 34 to receive suitable securing bolts for securing the rear flanges 34 to the rear panel 14.

When the cabinet is to be transported, the main body 12 may be collapsed to a substantially flat condition, as shown in Figure 2, after removal of the side panels, and the side panels 13, 13 may be packed along with the collapsed main body 12 in a substantially flat pack-

age of relatively small volume. When the cabinet is to be assembled, the main body 12 is unfolded to the expanded position thereof shown in Figure 3, and the side panels 13, 13 are engaged over the side portions of said main body, in the manner shown in Figures 6 and 7, said side panels are then fastened to the main body by means of the bolts above mentioned which are engageable through the bolt holes 36 and through the registering holes provided therefor in the posts 21 and the upper and lower corner portions of the rear panel 14. It will be readily apparent that the cabinet may be assembled in a relatively short period of time, and with only a small expenditure of effort, and furthermore that only eight bolts are required to secure the side panels 13, 13 to the sides of the main body 12 to complete the assembly.

As shown in Figure 3, the inner elements 37 of the channel-shaped flanges 35 are suitably notched at 38 and 39 to accommodate hinges connecting the doors 29, 29 to the frame posts 21, 21.

While a specific embodiment of an improved foldable cabinet has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. In a foldable cabinet, a back panel having side edges and an upper edge, forwardly projecting side and top flanges on said side and upper edges, a plurality of vertically spaced shelves having front and rear corners, the rear corners of the shelves being pivoted to said side flanges forwardly of the back panel, a top panel having front and rear corners, the rear corners of the top panel being pivoted to the back panel side flanges above the shelves, a front frame positioned forwardly of the shelves, said front frame comprising vertical side posts and top and bottom horizontal bars extending between and fixed to upper and lower portions of the posts, said posts comprising channels having laterally inwardly projecting flanges and rearwardly projecting flanges, the forward corners of the shelves and of the top panel being pivoted to the rearwardly projecting flanges of the frame posts, doors in said frame having laterally outward side edges hinged to the channels, removable side panels having back and front vertical edges, laterally inwardly projecting

flanges on the back edges of the side panels engaged behind the back panel, channel flanges on the front edges of the side panels engageable around the front frame channels, first securing means separably connecting the side panel channel flanges to the front frame channels, and second securing means separably connecting the side panels to said back panel.

2. In a foldable cabinet, a back panel having side edges and an upper edge, forwardly projecting side and top flanges on said side and upper edges, a plurality of vertically spaced shelves having front and rear corners, the rear corners of the shelves being pivoted to said side flanges forwardly of the back panel, a top panel having front and rear corners, the rear corners of the top panel being pivoted to the back panel side flanges above the shelves, a front frame positioned forwardly of the shelves, said front frame comprising vertical side posts and top and bottom horizontal bars extending between and fixed to upper and lower portions of the posts, said posts comprising channels having laterally inwardly projecting flanges and rearwardly projecting flanges, the forward corners of the shelves and of the top panel being pivoted to the rearwardly projecting flanges of the frame posts, doors in said frame having laterally outward side edges hinged to the channels, removable side panels having back and front vertical edges, laterally inwardly projecting flanges on the back edges of the side panels engaged behind the back panel, channel flanges on the front edges of the side panels engageable around the front frame channels, first securing means separably connecting the side panel channel flanges to the front frame channels, and second securing means separably connecting the side panels to said back panel, said first and second securing means comprising removable bolts.
